TURRET CONSTRUCTION

Harry A. Sutton, San Diego, Calif., assignor to
Consolidated Vultee Aircraft Corporation, a
corporation of Delaware

Application May 12, 1942, Serial No. 442,607

7 Claims.

(Cl. 89—36)

The present invention relates to turret constructions and more particularly to improvements in the fairing and streamlining of the spaces between a movable turret and the fixed structure upon which it is carried.

In movable turrets for military vehicles, such as aircraft, tanks, boats and the like, it is of major importance to provide a construction in which the gunner or operator has a wide field of fire which is unobstructed by the adjacent body structure of the vehicle. At the same time it is also of importance that any re-entrant areas or spaces between the movable turret and the fixed body be filled out or aerodynamically faired by structures which do not impede the movement of the turret or the operations of its occupant. These considerations are particularly important in connection with aircraft and other high speed vehicles in order that the aerodynamic drag of the turrets and adjacent portions is not unduly increased.

The present invention provides a satisfactory solution to these problems and discloses a construction for fairing the re-entrant areas adjacent a movable gun turret. This invention has been shown as applied to the nose turret of a large flying boat and is arranged such that as the turret is traversed laterally in either direction a movable fairing is automatically rotated therewith to prevent obstruction of the vision and firing field of the gunner. These side fairings or shields are also arranged such that they automatically follow the return movement of the turret as it is moved towards its normal or central position.

It is accordingly a major object of the present invention to provide means for maintaining the streamline integrity of a body adjacent a movable turret without limiting the firing angles of the gun mounted within the turret, or the vision of the gunner. It is a further object to provide such a fairing for a gun turret which is automatically retracted as a result of corresponding movement of the gun turret and which is also automatically returned to its fully extended position upon movement of the turret to its normal or central position.

A further object of the present invention resides in the provision of streamlined fairing elements which are automatically retractable and extensible and do not require the attention of the gunner for their operation. A further object resides in the provision of retractable turret fairings of a unique shape and construction and of a novel mounting arrangement which permits their

readily being moved in either direction and which does not interfere with the mounting or movements of the gun turret.

Other objects and advantages of the present invention will become apparent to those skilled in the art after a reading of the following specification and the attached drawings forming a part hereof, in which:

Fig. 1 is a side elevation of a gun turret mounted in the nose of an aircraft and to which the fairings of the present invention have been applied;

Fig. 2 is a similar view of the same in which the turret has been traversed toward the reader and the turret fairing is shown in a retracted position;

Fig. 3 is a detailed side elevational view of the turret fairing shown in Figs. 1 and 2;

Fig. 4 is a detailed elevational view of the same fairing as viewed looking forward;

Fig. 5 is a detailed plan view of the same fairing;

Fig. 6 is an enlarged sectional plan view of the lower portion of the fairing as taken along the lines 6—6 of Fig. 3; and

Fig. 7 is a detail sectional view of the track and the rollers carried upon the lower portion of the fairing, the view being taken along the lines 7—7 of Fig. 6.

Referring now to Figs. 1 and 2, 10 designates the body or hull portion of an aircraft to which the present invention has been applied. It will be understood that this invention is equally applicable to gun turrets on other vehicles, such as armored cars, tanks and boats, and the nose turret of an aircraft has been selected only by way of showing a preferred embodiment. The numeral 11 indicates the bow structure of the flying boat in the upper or nose portion of which there is provided an opening for a spherical type gun turret 13.

The gun turret 13 is preferably constructed of a spherical framework 132 within which is supported transparent part-spherical panels 133 within which is provided an apertured ring 131 to accommodate a machine gun 14, or other ordnance or camera gun which it may be desired to operate from the turret. The nose turret 13 is preferably of true spherical shape of sufficient diameter to be occupied by a gunner and contains a sufficient quantity of ammunition and other equipment and instruments normally required by the gunner's or photographer's operations. The turret is preferably mounted for horizontal or lateral traverse about the vertical

axis B—B, as well as vertical rotation for gun elevation about the transverse axis passing through the point 0 at the intersection of the vertical axis B—B with the horizontal longitudinal axis A—A. The point "0" accordingly forms the geometrical center of the substantially spherical outer surface of the turret 13.

Inasmuch as the mounting and operating details of the gun 14 and turret 13 form no part of the present invention they have not been shown in detail in the drawings. It will be deemed sufficient, however, to state that the bow gun 14 is mounted in a hydraulic power-driven turret which is composed of two major units, the enclosure and the gimbal. The gimbal, which is not shown, permits horizontal rotation, and trunnions permit movement in azimuth; the gimbal is power operated and is set on rollers in a track which is rigidly attached to the airplane structure. The enclosure or turret 13, which is pivoted directly to the gimbal through the side supports 15, rotates vertically to permit changes of gun elevation, and is power actuated. The gunner's seat and gun mount are an integral part of the enclosure frame, in order that any vertical movement of the enclosure also elevates the gun and the gunner. Horizontal movement of the gimbal rotates the entire turret assembly. An entrance door inside the hull provides access to the enclosure. The gun 14 is suitably fastened to the gun mount and the opening 131 in one of the transparent enclosure panels 133 allows space for the gun muzzle to be inserted.

The bow or nose of the flying boat 10 converges in a continuous streamlined surface toward the nose opening in which the turret is disposed. In the region of the forward transverse bulkhead (not shown) there is preferably provided a pair of side windows 101 as well as a roof or deck window 102. A typical transverse cross section of the hull just forward of these windows would provide a depth through the hull of considerably greater dimension than the beam or width, with the upper portion following an elliptical or well-rounded form and the sides approaching parallelism. Extending forward from the first transverse bulkhead there is disposed a fixed fairing portion 12, the surfaces of which carry forward a continuation of the streamlined shape of the after portion of the flying-boat body 10. This fixed fairing portion 12 has its leading edge cut back in a lateral and downward sense to provide an opening within which there is rotatably nested the movable side fairings 16.

Each of the movable fairings 16 is of a curvilinear form, the surfaces of which are shaped to continue forwardly the streamlined contour of the hull body and the adjacent fixed fairing portion 12. The lower or outer edges of each fairing 16 are straight in a horizontal sense as shown in Fig. 6 to provide for engagement with the guide tracks 17 to be described below. In a transverse direction the movable fairings 16 provide a continuation of the rounded upper deck portion and the less sharply curved side portions typical of the larger cross sectional shapes taken through more rearward sections of the hull 10. The rear edge of the fairing 16 is preferably formed to be substantially parallel to the forward edge of the fixed fairing 12. The forward edge of the movable fairing 16 is, however, forwardly curved both at its upper and lower portions to fair itself closely toward the spherical outer surfaces of the turret 13 and the lateral turret supports 15, between which the fairing 16

is adapted to nest or telescope with minimum clearances.

The retractable turret fairings 16 are preferably mounted to be rotated about separate laterally spaced vertical pivot axes C—C which are rearwardly spaced from the vertical axis B—B of the gun turret and spaced a lesser distance at either side of the longitudinal center line of the body 10, as is clearly shown in Fig. 5. The upper portion of each fairing 16 is provided with an apertured lug 160 each of which is provided with an opening to accommodate a vertically disposed bearing pin 18. The pins 18 are also mounted and retained within the forward central portion of the fixed fairing 12 by means of aligned lugs 121, as shown in Fig. 3. The lower or base portion of each movable fairing 16 is provided with suitable rollers 166 and 167 for guided movement within the arcuate track 17, which is fixedly supported upon the aircraft structure. The fairings 16 are also intermediately provided with stiffeners or formers 165a and window openings which are suitably provided with transparent panels 161. The inner wall 16a of the fairing is provided with an opening opposite the panel 161.

The lower portion of the movable fairing 16 is provided with a segmental shaped channel portion 164 suitably fastened to the inner and outer surfaces of the fairing and having fastened thereto downwardly extending angle brackets 165 from which are pivotally supported the vertical and horizontal rollers 166 and 167. The front or outer sheet of the fairing 16 is preferably continued around the leading edge 162 and suitably fastened to the inner sheet 16a. A channel shaped plate 164a is disposed between the rearward edges of the inner and outer sheets forming a trailing edge at 163 and is provided at its lower extremity with a clip 176. The triangular box type construction of the fairing 16 serves to give it rigidity to pivot and roll freely while maintaining the required clearances between the turret and the fixed body to merge the joint therebetween.

The track 17 is rigidly supported upon the aircraft structure and is formed of a curved angle section 171 to which is fastened an outwardly extending angle 172 of deeper section and an outwardly and upwardly facing channel section 173 as shown in detail in Fig. 7. The outstanding leg of the angle 172 and the web of the channel 173 are spaced to closely accommodate the horizontal pivoted roller 167 and the flanges of the channel are disposed such that they similarly accommodate the vertically pivoted rollers 166. A bungee cord 174 is provided to return each of the side fairings 16 to its forward position upon return of the turret to its normal central position. Each bungee cord 174 is guided at its forward portion over an idler sheave 175 which is pivotally mounted upon the aircraft structure in the region of the fixed track 17. The rearward terminal of the bungee cord is attached to an apertured fitting 177 supported upon the aircraft structure and the forward terminal after running over and returning a short distance rearwardly from the sheave 175 is anchored to an aperture in the clip 176 carried by the fairing 16. Each side support 15 of the turret is provided with a laterally extending lug or detent 151 which is adapted to engage the reinforced leading edge portion 162 of the respective fairings 16 upon lateral and rearward traverse of the turret beyond a predetermined amount and the bungee cords serve to au-

tomatically return the fairing to its forwardly extended position.

Referring again to Fig. 1, it will be seen that the turret 13 is substantially in its central or normal position and can be laterally traversed toward the reader through a limited arc before the lug 151 comes in contact with the leading edge 162. Beyond this point it is considered that the fairing 16 interferes with the vision and firing capabilities of the gunner. Accordingly, as the turret is continued in its lateral rotation the lug 151 making contact with the fairing 16 at its leading edge 162 causes the fairing to be rotated rearwardly about the vertical axis C-C passing through its upper pivotal connection 18 and with its lower portion moving arcuately rearwardly and inwardly along the track 17. As the fairing 16 is automatically retracted rearwardly the bungee cord 174, which is initially tensioned in its normal position, has its tension increased such that as the turret is returned to its central position the bungee cord urges the fairing forward in continual contact with the lug 151 until the fairing reaches its forward position as determined by the stop 178 at the forward end of the track upon its being contacted by the adjacent roller 167. The hydraulic turret control imparts sufficient motive force to the turret that the considerably lighter action of the bungee cord exerted through the side fairings is readily overcome both through movement and in the locked positions of the turret. In the return movement of the turret the lug 151 first serves as a detent in limiting the following movement of the fairing 16 to contact with the turret side 15, and as the movement continues the stop 178 at the end of the track serves as a secondary detent to limit the fairing to its extreme forward position.

Other advantages of the present invention both with respect to its general arrangement and details which may become obvious to those skilled in the art after a reading of the present description are intended to come within the scope of the present invention as more particularly defined in the appended claims.

I claim:

1. In turret construction, a vehicle body, a turret movably carried within an opening in said body, a fairing element movably carried upon said body disposed between the same and said turret, and detent means associated with said turret and fairing for imparting to said fairing movements of said turret beyond a predetermined extent.

2. In aircraft, a body having an opening therein, a turret rotatably mounted upon said body within said opening, a movable fairing carried upon said body adapted to merge the joint between said turret and said body, detent means carried by said turret constructed and arranged to carry said fairing with said turret during predetermined excess movements of said turret, and means to urge said fairing into its initial position upon return of said turret to its normal position.

3. In aircraft, a body having an opening there- 65

in, a turret rotatably mounted upon said body within said opening, a movable fairing carried upon said body adapted to merge the joint between said turret and said body, detent means carried by said turret constructed and arranged to carry said fairing with said turret during predetermined excess movements of said turret, means to urge said fairing into its initial position upon return of said turret to its normal position, and second detent means fixed with respect to said body constructed and arranged to limit return movement of said fairing prior to the return of said turret to its normal position.

4. In aircraft, in combination, an aircraft body 15 having an opening therein, a gun turret rotatable within said opening about a vertical axis carried upon said aircraft, a fairing movably carried upon said body disposed between the said turret and the adjacent edges of said opening, said turret being movable about said axis both with and with respect to said fairing, and detent means associated with said turret and said fairing for imparting said concurrent movements to said fairing upon movement of said turret beyond a predetermined extent.

5. In aircraft, a body having an opening in the nose portion thereof, a turret rotatably mounted upon said body on a vertical axis for rotation within said opening, a fairing movably supported upon said body for concurrent rotation with said turret and within said opening, and detent means associated with said turret and said fairing for imparting to said fairing movements of said turret beyond a predetermined extent whereby said fairing fairs the joint between said turret and the edges of said body opening in a plurality of positions into which said turret is movable.

6. In aircraft, in combination, a body having a nose portion with an opening in an exterior surface thereof, a turret pivotally mounted within said opening such that a gap is created between the surface of said turret and the edge of said body opening, a fairing element movably supported upon said body normally serving to provide a streamlined continuation of the exterior surfaces of said turret and said body across said gap and stop means associated with said turret and said fairing for imparting to said fairing movements of said turret beyond a predetermined extent.

7. In aircraft turret construction, an aircraft body having an opening therein, a turret movably carried by said body within said opening, arcuate 55 guide means carried by said aircraft body adjacent a lateral side of said turret, pivotal means carried by said aircraft body substantially above said turret, a fairing element movably supported by said aircraft body upon said guide and pivotal means, and detent means associated with said turret and said fairing for imparting to said fairing movements of said turret beyond a predetermined extent.

HARRY A. SUTTON.
